WRIGHT DURYEA, OF GLEN COVE, NEW YORK.

Letters Patent No. 106,141, dated August 9, 1870.

ELECTRO-MAGNETIC LOW-WATER ALARM FOR STEAM-BOILERS.

The Schedule referred to in these Letters Patent and making part of the same

To all whom it may concern:

Be it known that I, WRIGHT DURYEA, of Glen Cove, in the county of Queens and State of New York, have invented a new and useful Electro-Magnetic Low-Water Alarm for Steam-Boilers; and I do hereby declare that the following is a full, clear, and exact description of the same, reference being had to the accompanying drawing forming part of this specification.

The object of this invention is to provide with greater certainty for the sounding of an alarm at any distance from a steam-boiler, whenever the water therein shall fall below a certain level.

It consists in arranging, within or in suitable connection with the boiler, a portion of the conductor of an electric circuit, in which there is placed, outside of the boiler, a suitable electro-magnetic call or alarm, and in providing, within the said circuit, a circuit-breaker, which is so actuated by a float or other device, which depends for its position on the height of the water in the boiler, that the opening and closing of the circuit shall be produced by the rise and fall of the water above and below the desired level, and that, when the water gets below that level, the call or alarm shall be sounded.

The invention is capable of many modifications, but, to enable others to construct and apply it, I will proceed to describe that form which I consider the simplest, and which is illustrated in the accompanying drawing, in which—

Figure 1 is a central vertical section, and

Figure 2 a horizontal section in the line $z z$ of fig. 1.

Similar letters of reference indicate corresponding parts in both figures.

A is a tube, of glass or other material, which is a non-conductor of electricity, inserted through and tightly clamped in a stuffing-box, B, which is screwed into or otherwise tightly secured in the top of the boiler. This tube extends downward below the lowest desirable water-level.

a is the packing, of India rubber or other suitable material, by which the tube is firmly clamped, and by which leakage of steam around the tube is prevented.

Within the tube A two smaller tubes, C C', of similar non-conducting material, are secured and packed, by suitable cement, such as a mixture of red lead, linseed oil, and iron filings, which is impervious to water and steam.

Through these tubes C C' are inserted two wires, b b',

which form portions of the electric circuit or conductor, and these wires are secured and packed in the said tubes by cement of similar nature to that employed to secure the tubes C C' in the larger tube A.

The wires, which are insulated from each other by small glass tubes, and insulated from the boiler by the larger tube, have their lower ends extended through the bottoms of all the tubes, and have elastic terminations, which are turned up, as shown at c c, in fig. 1, to enable the circuit to be closed between them by the circuit-breaker, as will be presently described.

The upper portions of the wires, which extend through the upper ends of the tubes, are intended to be connected with a galvanic battery, and with an electro-magnetic "call," such as is used in telegraph offices, or with an electro-magnetic "alarm," such as is used in burglar-alarms, or with any electro-magnetic apparatus capable of producing sounds by striking a bell, or acting on any other sounding device. This call, alarm, or sounding apparatus may be in the engine-room, or in any place more or less distant from the boiler, where it may be desirable to have known the deficiency of water therein.

D is a circuit-breaker, consisting of a hollow-metal float, of annular form, fitted to slide very freely upon the exterior of the tube A, and floating on the water in the boiler, so that it will move up and down the tube as the level of the water varies.

This circuit-breaker or float is so applied, and the elastic terminations of the wires c c are so arranged that, while the water is above the lowest level to which it is desired that it shall fall, the circuit-breaker or float shall be out of contact with the wires, and the circuit shall remain open, but whenever the water falls to that level, it, the circuit-breaker or float, shall come in contact, as shown in dotted outline in fig. 1, with both of the terminations c c of the wires, and so close the circuit and set the call or alarm in operation.

What I claim as my invention, and desire to secure by Letters Patent, is—

The combination of the floating circuit-breaker D, the insulating-tube A, and the insulated circuit-wires b b', to operate substantially as herein described, for the purpose set forth.

WRIGHT DURYEA.
